[57] CLAIM

The ornamental design for a slam latch, as shown and described.

DESCRIPTION

FIG. 1 is a front elevational view of a slam latch showing our new design;

FIG. 2 is a top plan view thereof, the bottom being a mirror image of that shown;

FIG. 3 is a rear elevational view thereof;

FIG. 4 is a right side elevational view thereof; and,

FIG. 5 is a left side elevational view thereof.

The broken line-disclosure of a panel in which the slam latch is mounted is for illustrative purposes only and forms no part of the claimed design.
